DESIGN FOR A RANGE OR SIMILAR ARTICLE

Clifford A. Sipe, Shelby, Ohio, assignor to Westinghouse Electric & Manufacturing Company, a corporation of Pennsylvania

Application March 28, 1936, Serial No. 61,837

Term of patent 7 years

To all whom it may concern:

Be it known that I, Clifford A. Sipe, a citizen of the United States residing at Shelby in the county of Richland and State of Ohio, have invented a new, original, and ornamental Design for a Range or Similar Article, of which the following is a specification, reference being had to the accompanying drawing, constituting a part thereof in which the figure is a perspective view of a range showing my new design. The dominant features of my design reside in the portions shown in full lines.

I claim:

The ornamental design for a range or similar article substantially as shown and described.

CLIFFORD A. SIPE.
